Patented Nov. 4, 1924.

Des. 65,900

UNITED STATES PATENT OFFICE.

HARVEY S. COOK, OF VALPARAISO, INDIANA.

DESIGN FOR A HYPODERMIC SYRINGE.

Application filed May 2, 1921. Serial No. 466,227. Term of patent 3½ years.

To all whom it may concern:

Be it known that I, HARVEY S. Cook, a citizen of the United States, residing at Valparaiso, in the county of Porter and State of Indiana, have invented a new, original, and ornamental Design for Hypodermic Syringes, of which the following is a specification, reference being made to the accompanying drawing, forming a part thereof.

The figure in the drawing shows a hypodermic syringe embodying my new design.

I claim:

The ornamental design for a hypodermic syringe, as shown:

HARVEY S. COOK.

Witnesses:

ROY M. HALL,
EMMETT E. HALL.
